(57) **CLAIM**

The ornamental design for a display screen with animated graphical user interface, as shown and described.

DESCRIPTION

FIG. 1 is a front view of a display screen with animated graphical user interface showing a first image in a sequence of a first embodiment of the design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a front view of a display screen with animated graphical user interface showing a first image in a sequence of a second embodiment of the design;

FIG. 10 is a second image thereof;

FIG. 11 is a third image thereof;

FIG. 12 is a fourth image thereof;

FIG. 13 is a fifth image thereof;

FIG. 14 is a sixth image thereof;

FIG. 15 is a seventh image thereof; and,

FIG. 16 is an eighth image thereof.

The dashed lines, broken text, and broken graphics illustrate portions of the display screen with animated graphical user interface that form no part of the claimed design. The appearance of the animated graphical user interface sequentially transitions between the images shown in FIGS. 1-8 and 9-16. The process or period in which one image transitions to another forms no part of the claimed design. In FIGS. 4 through 8 and 12 through 16 the shopping bag menu icon moves downwards and then upwards to its starting position.
